US0D1111677S

(12) United States Design Patent (10) Patent No.: US D1,111,677 S
(45) Date of Patent: * Feb. 10, 2026

(54) COUNTERTOP FOOD TRAY

(71) Applicant: Steven Hutnick, Naples, FL (US)

(72) Inventor: Steven Hutnick, Naples, FL (US)

() Term: 15 Years

(21) Appl. No.: 29/900,713

(22) Filed: Aug. 24, 2023

(51) LOC (15) Cl. 07-01

(52) U.S. Cl.

USPC D7/554.2

(58) Field of Classification Search

USPC ..... D3/304, 308, 314, 315; D7/316, 317, D7/318, 312, 300, 368, 372, 376, 378, D7/383, 384, 387, 399, 409, 412, 413, D7/414, 415, 550.1, 553.2, 554.2, 554.3, D7/554.4, 602; D23/200; D19/92 CPC A21C 1/02; A21C 1/04; A23N 1/00; A23N 1/02; A47J 43/04; A47J 43/25; A47J 43/042; A47J 43/046; A47J 43/0722; A47J 47/16; A47G 19/02; A47G 19/06; A47G 23/06; B65D 1/00; B65D 1/24; B65D 1/34; B65D 1/36; B65D 5/00

(57) CLAIM

The ornamental design for a countertop food tray as shown and described.

DESCRIPTION

FIG. 1 is a front perspective view of a countertop food tray showing my new design;

FIG. 2 is a front exploded view thereof;

FIG. 3 is a top view thereof;

FIG. 4 is a bottom view thereof;

FIG. 5 is a side view thereof; and,

FIG. 6 is a side cutaway view thereof.

The broken lines shown in the drawings illustrate portions of the countertop food tray that form no part of the claimed design.

1 Claim, 6 Drawing Sheets
